CLAIM

The ornamental design for a bottle, as shown and described.

DESCRIPTION

FIG. 1 is a perspective view of a bottle.

FIG. 2 is a front view of the bottle.

FIG. 3 is a back view of the bottle.

FIG. 4 is a left view of the bottle.

FIG. 5 is a right view of the bottle.

FIG. 6 is a top view of the bottle; and,

FIG. 7 is a bottom view of the bottle.

The broken lines in the drawings of the bottle illustrate the portions of the bottle that form no part of the claimed design.
